1

This invention relates to new and useful improvements in the viscosity reduction of petroleum mahogany sulfonate hydrocarbon solutions.

Petroleum mahogany sulfonate solutions in organic solvents of the water immiscible type are used for a variety of purposes such as wetting agents, emulsifying agents and the like. Ordinary petroleum mahogany sulfonates impart to their solutions a relatively high viscosity. In some cases this high viscosity is not critical regarding the purpose for which the sulfonate solutions are to be used. There are, however, many cases in which a relatively high viscosity is undesirable or detrimental to their intended use or application. This is, for example, true in textile processing such as of wool, worsted, rayon, viscose or the like, in which the various processing steps involved in the conversion of the raw material into fibres, the formation of the fibres into threads and the weaving of the threads into fabric, require the presence of a lubricating agent having a Saybolt viscosity of below 600 and preferably below 300 seconds Saybolt at 100° F. The latter is particularly true of textile lubricants used in the processing of synthetic fibres. In the case of textile processing it is for instance desirable to have a hydrocarbon textile lubricant composition with a sulfonate content of in excess of 28% mahogany sulfonates so as to render the composition not only readily and spontaneously emulsifiable but also to make the same readily wettable or rewettable on the fibre to thereby impart to the textile material substantial self-scourability. Hydrocarbon solutions of the textile lubricant type and containing in excess of 28% of petroleum mahogany sulfonates possess, however, a viscosity far in excess of 600 seconds Saybolt at 100° F. and usually a viscosity in excess of 1000 seconds Saybolt at 100° F. For this reason it has been in the past necessary in such cases to limit the sulfonate content to a maximum of approximately 15% in order not to exceed the usable viscosity for textile material treating purposes. Another example is the use of petroleum mahogany sulfonates in the compounding of cutting oil bases in which the relatively high viscosity and tackiness imparted to the composition by the sulfonate is an undesirable aspect interfering in many respects with the proper ease of application and use.

The relatively high viscosity of petroleum mahogany sulfonates in organic solvents is normally not subject to reduction by the addition of relatively low viscous diluents or thinning agents. This requires agents of such relatively

2

low viscosity that they interfere with the lubricating properties of the composition. Furthermore, these solvents are then of the type which easily evaporate. This is particularly critical in the case of textile treating materials since the use of such thinning solvents will leave behind on the fibre upon evaporation a viscous sticky impregnant without adequate lubricating capacity on the fibre and will also interfere with the scourability of the impregnated material. On the other hand thinning with a solvent of the lubricant type diluent will not obtain the desired result as it is necessary to add so much of the diluent as to bring the sulfonate content to below that necessary for adequate emulsification or other purpose for which the composition is designed.

One object in accordance with the invention comprises inter alia the viscosity reduction of a petroleum mahogany sulfonate solution in a substantially water immiscible organic solvent.

This and further objects of the invention will appear from the following description.

In accordance with the invention a suitable petroleum mahogany sulfonate solution in an organic substantially water immiscible solvent for said sulfonate is reacted with an oxidation agent in amount and for a period of time sufficient to appreciably reduce the normally relatively high viscosity of said solution due to the sulfonate dissolved therein and preferably reduce said viscosity by at least one-third, said oxidation agent being one having an oxidation potential by virtue of the existence or liberation of O₂.

Suitable oxidation agents may be either of the inorganic or organic type. Among inorganic oxidation agents useful in accordance with the invention satisfactory results may be obtained, for instance, with chromic acid, dichromates, permanganates, perchlorates, peroxides and similar materials. Among the organic oxidation agents may be recommended particularly organic peroxides and hyperperoxides, both aliphatic and aromatic, including for example butyl hyperperoxide, acetyl peroxide, benzoyl peroxide and like materials. The reaction conditions under which the oxidation agents in accordance with the invention produce an oxidation potential, including conditions of pH range, are well known in the art and need not be further exemplified here.

The solvents that may be used for preparation of the petroleum mahogany sulfonate solution to be treated should be substantially neutral to the action of the oxidation agent, are preferably such as will not appreciably dissolve inorganic salts,

and should be liquid at normal temperatures. Suitable solvents that may be used in the practice of the invention are, for instance, petroleum oil distillates or any fraction thereof, benzol and its homologs, naphtha, carbon tetrachloride, tetrachlorethane, chloroform, etc., and in general any aromatic or aliphatic or aryl or aralkyl hydrocarbon or hydrocarbon mixture, including their halogenated derivatives of the aforescribed character and nature. In many cases, particularly where the solvent is to be removed after the viscosity reducing treatment, it is desirable to have the boiling range of such solvent sufficiently low to permit removal in the customary manner, such as by distillation in *vacuo* or otherwise, without causing thereby any decomposition of the mahogany sulfonates. In such cases it is of advantage that the boiling point be so low and preferably between 75 and 250° F. as to enable the removal of the solvent at ordinary temperatures without the necessity of resorting to vacuum distillation.

The petroleum mahogany sulfonate which is subjected to the viscosity reduction is normally one derived from the acid refining, with fuming sulfuric acid, of a petroleum oil distillate stock under sulfonating conditions of acid amount and temperature in accordance with conventional refining practice. In such conventional fuming sulfuric acid refining an oil layer and acid sludge layer are formed, the former containing dissolved therein petroleum mahogany sulfonic acids collectively referred to as mahogany petroleum sulfonic acids. These are recovered from the oil layer in accordance with conventional methods in the form of solutions of these sulfonic acids or their salts (the latter being collectively termed "petroleum mahogany sulfonates") in a portion of the oil relatively tenaciously occluded by these sulfonic bodies. The conventional recovery of petroleum mahogany sulfonates includes neutralization of the oil layer with caustic soda resulting in the formation of the petroleum mahogany sodium sulfonates. The occluded oil is generally referred to in the art as "retained oil." The petroleum sulfonic acids or sulfonate oil compositions normally contain about 30 to 35% of retained oil and 65 to 70% of the petroleum mahogany sulfonic material. Depending upon the type and origin of petroleum oil distillates from which these sulfonate oil solutions or stocks are derived, they contain sulfonates of varying averaged molecular weights. For convenience therefore the sulfonate stocks are identified by their average molecular weights. Thus, a 420 or 450 sulfonate stock is a stock in which the sulfonates have an average molecular weight of 420 or 450 respectively.

In the practical application of the invention the crude mahogany sulfonate in the organic solvent solution is intimately contacted with the oxidation agent. Depending upon the nature of the oxidation agent, the same may be added in the form of a suitable aqueous or organic solvent solution, or may be added as such. Some of the organic type oxidation agents are preferably added as such since they are soluble in the type solvent used for the sulfonate solution to be treated. It is, however, also possible to add oxidation agents that are not so soluble in such solvent in the form of fine dispersions and maintaining suitable agitation so as to assure continued intimate contact for the reaction. In most cases the inorganic oxidation agents, such as dichromates, chromic acid, etc., are preferably

added in aqueous solution. In the case of dichromates, the oxidation reaction is carried on on the acid side and in effect the oxidation potential in such case is primarily that existing by reason of the formation of chromic acid. The treatment with the oxidation agent in accordance with the invention is continued until the desired viscosity reduction is obtained, which may be ascertained by the drawing of periodic samples and the examination thereof on a suitable viscosimeter. Maximum viscosity reduction may be accompanied by color reduction, which in many cases may be used as an indication of the completion of the viscosity reducing reaction. Color reduction to a Lovibond color value (10% white oil solution $\frac{1}{2}$ " cell) of less than 8R and preferably down to 2-3R is usually desirable. Wherever the oxidation agent itself possesses a tintorial value, as is the case for instance with dichromates chromic acid, permanganates, etc., color reduction cannot be used as a test.

Where an alkaline or acid pH may be called for to establish an oxidation potential for a particular oxidation agent in accordance with the invention, it is always to be recommended that an excess of alkalinity or acidity should be avoided. Such excess may be detrimental to the efficiency of the viscosity reduction and may furthermore give rise to the partial decomposition of the sulfonates, as well as in many cases to an undesirable color deterioration, rather than color improvement in the resultant products. Since it is in many cases desirable to utilize the ultimate product in substantially neutral form, it may be necessary when the establishing or existence of an oxidation potential calls for an acid pH, to neutralize the product resulting from the treatment. In many instances such neutralization, however, is accompanied by some increase in viscosity from that obtaining in the treated product. This viscosity increase or reversion is usually not sufficiently critical to interfere with the ultimately desired reduced viscosity of the final product and for the purpose for which it is intended. By reason of the viscosity reversion upon neutralization, however, it may be in many cases of advantage, particularly when lower range viscosities are desired, to select as the oxidation agent one with which the treatment may be carried out for the establishing of an oxidation potential at a neutral to alkaline pH so as to render unnecessary a neutralization of the reaction products. In this case it is usually of advantage to select an agent permitting the establishing of an oxidation potential at a pH range of from 7 to 8.5

Depending upon the oxidation agent selected, satisfactory results are ordinarily obtained with substantially from 0.25 to 3% of oxidation agent by weight of sulfonates present in solution.

The temperature of reaction is ordinarily not critical. The reaction, however, may be facilitated by increasing the temperature to, for example, a preferred temperature of from 120 to 200° F. This is particularly desirable with more heavily viscous solutions, as the higher temperature will increase the fluidity of the solution, thus permitting more intimate contact between the reactants.

The extent to which low viscosity values may be obtained depends, at least to some extent, upon the type or origin of the petroleum mahogany sulfonate selected for the treatment. Ordinarily higher average molecular weight sulfonates possess a higher viscosity and the resulting viscosity after treatment is usually commensurately higher than the viscosity after treatment of a

comparative sulfonate hydrocarbon solution which before treatment possessed a relatively lower viscosity and in which the sulfonate had a lesser average molecular weight.

The ration of petroleum mahogany sulfonate to solvent is, as a rule, not critical except that it is desirable to so adjust the ratio that the viscosity of the solution is sufficiently low at the desired or selected temperature of treatment to permit the intimate contact between the reactants. In most cases, however, a ratio of mahogany sulfonate to solvent of substantially 2 to 1 (by weight) will give satisfactory results. Sulfonate concentrations above 70 to 75% sulfonate content are normally not desirable for direct reaction without suitable extension. As a mode of agitation, any conventional method such as stirring, air-blowing, shaking, etc., may be used.

As above pointed out, the viscosity reducing reaction in accordance with the invention may be carried out with an organic solvent solution containing relatively high concentrations of petroleum mahogany sulfonate. In this case the resultant product is a concentrate which in many cases must be thereafter adjusted by the addition of organic solvent material of suitable viscosity, such as a suitable lubricant hydrocarbon, to the requisite petroleum mahogany sulfonate content desired for the specific purpose for which the composition is to be used. Thus, for instance, if it is desired to ultimately produce a textile treating oil having in excess of 28% petroleum mahogany sulfonate and a viscosity of less than 600 seconds Saybolt at 100° F., a concentrate having in excess of 40% and usually between 60 and 65% sulfonate, is first obtained after the viscosity reducing reaction in accordance with the invention, which product may be then extended by the addition of a suitable lubricant hydrocarbon, such as a mineral pale oil having a viscosity of 75 seconds Saybolt at 100° F. to a sulfonate content between 28 and 40% and a viscosity below 600 seconds Saybolt at 100° F.

Alternatively, the viscosity reducing reaction may be carried out with an organic solvent solution of a petroleum mahogany sulfonate already possessing the requisite final sulfonate content desired and intended for the purpose for which the viscosity reduced product is to be used. In that case it is also of advantage to select for the solution such solvent as is desired for the final product, i. e., if a textile lubricating oil is intended to be ultimately obtained, a textile lubricant having, for instance, a viscosity between 40 and 150 seconds Saybolt at 100° F. is selected as the solvent for the sulfonate. The product resulting from the viscosity reducing treatment is then per se usable after such further refining or purification as may be required for a textile treating oil.

Though in the operation of the novel viscosity reducing process any of the aforementioned solvents may be used with advantage, we prefer to use as the solvent that hydrocarbon fraction, the acid refining of which furnished the crude mahogany sulfonate stock and which is carried as "retained oil." The crude mahogany sulfonate-retained oil stock constitutes as such a convenient mahogany sulfonate solution that may be subjected directly to treatment in accordance with the invention.

Once a petroleum mahogany sulfonate has been subjected in suitable solvent medium to a viscosity reducing reaction in accordance with the invention, it is possible to remove the solvent if desired and recover the petroleum mahogany sul-

fonates as such substantially free from solvent. These sulfonates when redissolved in the solvent still exhibit in solution the same reduced viscosity which they possessed prior to the removal of the solvent.

The following examples are furnished by way of illustration and not of limitation:

Example I

10 100 lbs. of a petroleum mahogany sulfonate stock containing about 61% sulfonate, about 37% retained oil and about 2% water, was used. The stock was obtained from a Mid-Continent distillate subjected in the conventional manner to white oil refining with fuming sulfuric acid under sulfonating conditions. Mahogany sulfonates in the stock possessed an average molecular weight of 450, a Furol viscosity of 132 seconds at 210° F. Upon dilution with a mineral pale oil (75 seconds Saybolt at 100° F.) to a 30% sulfonate content, a viscosity of the solution of 1322 seconds Saybolt at 100° F. was obtained.

The original 61% sulfonate stock was acidified with 66% H₂SO₄ to about 2% free sulfuric acid content and 1 lb. of potassium dichromate was added with agitation at a temperature of about 180 to 200° F. Agitation and temperature were continued until a sample showed a viscosity reduction to 89 seconds Furol at 210° F. Upon dilution with a 75 vis. mineral pale oil to a 30% sulfonate content, a viscosity of the extended solution of 378 seconds Saybolt at 100° F. was obtained.

Example II

35 100 lbs. of the same 61% sulfonate stock used in Example I at a pH of about 7 to 8 was admixed with 1 lb. of potassium permanganate with agitation at a temperature of about 180 to 200° F. The treatment was continued until a sample showed a viscosity reduction of the mix to 51 seconds Furol at 210° F. Upon dilution with a mineral pale oil (75 seconds Saybolt at 100° F.) to a 30% sulfonate content, a reduced viscosity of 371 seconds Saybolt at 100° F. was obtained.

Example III

50 100 lbs. of the same 61% sulfonate stock used in Example I was admixed at a pH of from 7 to 8 with 5 lbs. butyl hyperperoxide with agitation, maintaining the temperature at about 180 to 200° F. The treatment was continued until a sample showed a reduced viscosity of about 60 Furol at 210° F. Upon dilution with a mineral pale oil (75 seconds Saybolt at 100° F.) to a 30% sulfonate content, a reduced viscosity of 482 seconds Saybolt at 100° F. was obtained.

Example IV

60 100 lbs. of the same 61% petroleum mahogany sulfonate stock used in Example I was admixed at a pH of from 7 to 8 with 2 lbs. of acetyl peroxide with agitation at a temperature of about 180 to 200° F. The treatment was continued until a sample showed a reduced viscosity of about 72 seconds Furol. Upon dilution with a mineral pale oil (75 seconds Saybolt at 100° F.) to a 30% sulfonate content, a reduced viscosity of 506 seconds Saybolt at 100° F. was obtained.

Example V

70 100 lbs. of a 450 Mid-Continent petroleum mahogany sulfonate stock containing about 61% sulfonate, about 37% retained oil and about 2% water, obtained by a fuming sulfuric acid treatment as specified in Example I, having a Furol

viscosity of 127 seconds at 210° F. was used. This stock when diluted with a mineral pale oil (75 seconds Saybolt at 100° F.) to a 30% sulfonate content showed a viscosity for the diluted stock of 1892 seconds Saybolt at 100° F. The original 61% sulfonate stock was admixed at a pH from 7 to 8 with 3 db's. of benzoyl peroxide with agitation maintaining the temperature at about 180 to 200° F. The treatment was continued until a sample showed a reduced viscosity of about 46 seconds Furol at 210° F. Upon dilution with a 7% mineral pale oil to a 30% sulfonate content, a viscosity for the extended solution of 385 seconds Saybolt at 100° F. was obtained.

Wherever the expression "oxidation agent" or such similar term is used herein, the same is intended to designate any agent or combination of agents having or capable of establishing an oxidation potential in the petroleum mahogany sulfonate solution, to be treated therewith, by reason of what is conventionally termed "available oxygen"; and in its broadest aspects includes "activated" oxygen, i. e., oxygen activated by suitable inductively or catalytically acting agents as is well-known in the art.

Within the broad concept of the invention it is of advantage to use an amount of oxidation agent equivalent to an "available" oxygen content of 0.2 to 1.5% O₂ by weight of sulfonate in solution.

The viscosity-reducing reaction in accordance with the invention is preferably carried out in the presence of relatively small amounts of an electrolyte, i. e., any compound ionizable in the medium in which the treatment is carried out to impart electrical conductivity to the medium. Most substantially water soluble organic and inorganic acids, bases and salts are such electrolytes. Many of the oxidation agents useful in accordance with the invention, as for example bichromates, chromic acid, permanganates, etc., are, as such, electrolytes. Others, such as benzoyl peroxide and similar compounds, are converted to yield electrolytes during the oxidation reaction. There are, however, some oxidation agents which are neither, as such, electrolytes nor are capable of producing an electrolyte during the oxidation reaction, such as, for instance, of hydrogen peroxide or the like. With these latter it may be necessary to add small amounts of an electrolyte such as 0.5-3% of NaCl, Na₂SO₄ or other suitable electrolyte material (by weight of sulfonate). For the purpose of obtaining the best effect of the electrolyte when carrying out the viscosity reducing reaction in accordance with the invention it is preferred to proceed in the presence of relatively small amounts of water as for instance conventionally present in sulfonate stocks. The water content is preferably at least 0.5 to 1% by weight of sulfonates in solution. Excess amounts of electrolyte or water are not critical (though they may entail the inconvenience of salt or water removal steps respectively).

The foregoing description is for purposes of illustration and not of limitation and it is therefore our intention that the invention be limited only by the appended claims or their equivalents wherein we have endeavored to claim broadly all inherent novelty.

We claim:

1. Process for reducing the viscosity of petroleum mahogany sodium sulfonate solutions which comprises reacting a petroleum mahogany sodium sulfonate solution in an organic substantially water immiscible solvent for said sulfonate,

said solution containing at least about 28% of said sulfonate and having a viscosity of in excess of 600 seconds Saybolt at 100° F. by reason of said sulfonate, with an oxidation agent having an oxidation potential in said solution by reason of "available" O₂, and selected from the group consisting of chromic acid, dichromates, permanganates, perchlorates and peroxides, in amount and for a period of time sufficient to reduce the said viscosity of such hydrocarbon solution to a point sufficiently low to yield for a sulfonate content of said solution of 28 to 40%, a viscosity below 600 seconds Saybolt at 100° F.

2. Process for reducing viscosity of petroleum mahogany sodium sulfonate solutions which comprises reacting a petroleum mahogany sodium sulfonate solution in "retained" oil, said solution containing in excess of 28% of said sulfonate and having a viscosity of in excess of 600 seconds Saybolt at 100° F. by reason of said sulfonate, in the presence of small amounts of water, and of an electrolyte with an oxidation agent, having an oxidation potential in said solution by reason of "available" O₂, and selected from the group consisting of chromic acid, dichromates, permanganates, perchlorates, and peroxides, in amount and for a period of time sufficient to reduce said viscosity to a point sufficiently low to yield for a sulfonate content of said solution of 28 to 40% a viscosity below 600 seconds Saybolt at 100° F.

3. Process in accordance with claim 2 in which said oxidation agent is an organic peroxide.

4. Process for reducing the viscosity of petroleum mahogany sodium sulfonate solutions which comprises reacting, in the presence of small amounts of water and of an electrolyte, a solution of in excess of 28% petroleum mahogany sodium sulfonate in a solvent for said sulfonate of the petroleum hydrocarbon type, said hydrocarbon solvent having a viscosity substantially between 40 and 150 seconds Saybolt at 100° F. and said solution having a viscosity of in excess of 600 seconds Saybolt at 100° F. by reason of said sulfonate dissolved therein, with an oxidation agent, having an oxidation potential in said solution by reason of "available" O₂, and selected from the group consisting of chromic acid, dichromates, permanganates, perchlorates and peroxides, and in amount equivalent to an available oxygen content of 0.2 to 1.5% O₂ by way of sulfonates in solution, and for a period of time sufficient to reduce the normally relatively high viscosity of said solution due to the said sulfonate dissolved therein to a point sufficiently low to yield for a sulfonate content from 28 to 40%, a viscosity below 600 seconds Saybolt at 100° F.

5. Process in accordance with claim 4 in which said oxidation agent is an organic peroxide.

6. Process for reducing the viscosity of petroleum mahogany sodium sulfonate solutions which comprises reacting, in the presence of small amounts of water and of an electrolyte, a solution in excess of 40% petroleum mahogany sodium sulfonate in "retained" oil, with an oxidation agent having an oxidation potential in said solution by reason of "available" O₂ in amount equivalent to "available" oxygen content of 0.2 to 1.5% O₂ by weight of sulfonates in solution, and selected from the group consisting of chromic acid, dichromates, permanganates, perchlorates and peroxides, and for a period of time sufficient to reduce the relatively high viscosity of said solution due to the said sulfonate dissolved therein to a point sufficiently low to yield upon

extension to a 28 to 40% sulfonate content with a solvent of the petroleum hydrocarbon type having a viscosity of from 40 to 150 seconds Saybolt at 100° F., a viscosity of the extended solution below 600 seconds Saybolt at 100° F.

7. Process in accordance with claim 6 in which said oxidation agent is an organic peroxide.
